[57] CLAIM

The ornamental design for adjustable directional lighting unit or similar article, substantially as shown and described.

DESCRIPTION

FIG. 1 is a bottom, left side perspective view of the adjustable directional lighting unit or similar article showing my new design;

FIG. 2 is a left side elevational view thereof, the opposite side being a mirror image;

FIG. 3 is a front elevational view thereof;

FIG. 4 is a top plan view thereof;

FIG. 5 is a rear elevational view thereof;

FIG. 6 is a bottom plan view thereof.

The support bracket is shown in broken lines for illustrative purposes only.
